UNITED STATES PATENT OFFICE.

JOSEPH COURVILLE, OF DETROIT, MICHIGAN.

PNEUMATIC PIANO-PLAYER.

No. 868,386.

Specification of Letters Patent.

Patented Sept. 17, 1907.

Application filed March 12, 1906. Serial No. 305,448.

To all whom it may concern:

Be it known that I, JOSEPH COURVILLE, a citizen of the United States, residing at Detroit, county of Wayne, State of Michigan, have invented a certain new and useful Improvement in Pneumatic Piano-Players; and declare the following to be a full, clear, and exact description of the same, such as will enable others skilled in the art to which it pertains to make and use the same, reference being had to the accompanying drawings, which form a part of this specification:

My invention relates to pneumatic piano players, and the objects of my improvements are to provide an improved pneumatic piano player in which a pneumatic apparatus may remain in position upon the piano without impeding the manipulation of the keys of the piano.

Referring to the accompanying drawing:—The figure is a cross section of a portion of a piano with an apparatus embodying my invention attached thereto.

A, is the key of the piano pivoted to a stationary support at a. A¹, is the end of said key, which is pressed down by the finger. A², is the inner end of said key, which is raised when the key is operated, and normally rests upon a stationary support A³.

B, is the striking hammer, B¹, a connecting rod, and B², a push rod guided to reciprocate vertically, and resting at its lower end upon the top of the standard a² rising from the key A.

30 B³, is a lug secured to the side of the push rod B² at the lower end of said rod.

The connecting rod B¹, and push rod B² constitute a hammer operating mechanism.

D, is a lever pivoted at D¹ to a standard D² rising 35 from the key A toward the end A² thereof.

D, is an adjustable stop by which the oscillatory motion of the lever D may be limited. Said stop is mounted upon one of the movable parts, D A, and adapted to strike against the other of said parts. The 40 lever D extends in the same plane as the key A, and the inner end of the key D comes beneath the lug B³.

C, is a bellows, such as is usually used in pneumatic piano players. c, is the hinged and movable side of said bellows. The upward movement of the bellows 45 c is limited by a stop C¹.

C², is a guided rod extending vertically downward, and provided with a presser-foot C⁴ at its lower end, which rests upon the front end of the lever D. The rod C² is secured at its upper end to the part c of the 50 bellows C by a convenient attachment C³, and is provided with means c⁴ for vertical adjustment.

The operation of the above described device is as follows:—When the key A is manipulated in the usual

way, the end A² thereof rises causing the stroke of the hammer B in the usual way. When the key A is oscillated the lever D is simply carried with it without disturbing the mechanism of the pneumatic apparatus. The location of the point of contact of the presser foot C⁴ and lever D relative to the pivotal point a of the key A is such that the contacting surfaces move longitudinal to each other. When the pneumatic apparatus is used, a vacuum is produced within the bellows C, which draws down the part c oscillating the lever D and raising the push rod B², so as to cause a stroke of the hammer B. Said push rod rises away from the standard a², so that the key A is not disturbed.

What I claim is:—

1. In a device of the kind described, the combination of the hammer operating mechanism, a key engaging said operating mechanism to actuate the same, a lever mounted 70 on said key and having an engagement with said operating mechanism independent of the key engagement, and a pneumatic apparatus adapted to actuate said lever to move said operating mechanism, substantially as and for the purpose described.

2. In a device of the kind described, the combination of a piano key having a pivot, a hammer operating mechanism resting on said key toward the inner end thereof, a lever pivoted upon said key engaging under a portion of said operating mechanism, and extending to a point located 80 approximately vertical with reference to the pivot of said key, and an actuating apparatus engaging said lever toward said point.

3. In a device of the kind described, the combination of a piano key having a pivot, a hammer operating mechanism resting on said key toward the inner end thereof, a lever pivoted upon said key engaging under a portion of said operating mechanism, extending to a point located 85 approximately vertical with reference to the pivot of said key, an actuating apparatus engaging said lever toward said point, and an adjustable stop upon the outer end of said lever.

4. In a device of the kind described, the combination of a hammer operating mechanism, a key adapted to actuate said operating mechanism, a lever mounted on 95 said key and engaging said operating mechanism, a pneumatic apparatus adapted to actuate said lever to move said operating mechanism, and an adjustable stop acting between said lever and key to limit the motion of said lever, substantially as and for the purpose described.

5. In a device of the kind described, the combination of the hammer operating mechanism, a pivoted key adapted to actuate said operating mechanism, a lever pivoted on said key having one of its ends nearer the pivot of said key than its other end, the inner end of said lever engaging under a portion of said operating mechanism, and a pneumatic apparatus adapted to act against the outer end of said lever to actuate said lever to move said operating mechanism.

In testimony whereof, I sign this specification in the 110 presence of two witnesses.

JOSEPH COURVILLE.
